UNITED STATES PATENT OFFICE.

CHARLES TETTENBORN, OF CINCINNATI, OHIO; KATE TETTENBORN, ADMINISTRATRIX OF SAID CHARLES TETTENBORN, DECEASED, ASSIGNOR TO FRANK S. MITCHELL, OF BEAVER FALLS, PENNSYLVANIA.

REFRIGERATOR-LINING.

1,224,235.

Specification of Letters Patent.

Patented May 1, 1917.

Application filed March 28, 1914. Serial No. 828,078.

To all whom it may concern:

Be it known that I, CHARLES TETTENBORN, residing at Cincinnati, Hamilton county, State of Ohio, have invented certain new and useful Improvements in Refrigerator-Linings, of which the following is a clear, full, and exact description, attention being called to the drawing which accompanies this application and forms a part thereof.

10 This invention concerns an article of manufacture which enters into the construction of refrigerators and serves as a lining for the chambers and compartments thereof. Such linings are made of various materials 15 and my invention concerns more particularly linings which are made of mineral matter, such as is involved in, or similar to that used in the manufacture of glazed earthenware, pottery ware, porcelain, etc.

20 One or more of such linings may be used in a particular style of refrigerator, this being dependent on the size of the refrigerator, its purpose and special requirements.

Such linings are used in connection with 25 an inclosure, the walls of which and the linings mentioned, are fitted to each other, reservation being made for insulating space between them and where more than one lining is used they are also fitted to each other so 30 as to produce in conjunction with the inclosure a compact structure.

The invention consists of the construction 35 of such linings as hereinafter described and claimed and as illustrated in the accompanying drawing in which:

Figure 1. shows such a lining in front-elevation.

Fig. 2. is a horizontal section through the upper part thereof.

40 Fig. 3. is a similar section through the lower part thereof.

Fig. 4. shows a detail of construction by means of an enlarged vertical section which is taken on line 4-4 of Fig. 3.

45 Fig. 5. in a view similar to Fig. 1, shows a modified construction.

Refrigerators are divided in compartments, there being usually at least two of them, one below the other, one to receive the 50 ice and the other serving as a chamber which receives food and provisions. Where there are additional provision chambers they may be below the ice-chamber or to the side thereof.

These compartments are open on one side, 55 which is usually the front side in refrigerators of the type here under consideration. Doors are provided to close this open side. The other sides are lined with various materials suitable for the purpose. 60

In some kinds of refrigerators these linings are made of glazed earthenware, such as pottery-ware or porcelain and are integrally connected to form a self-contained structure. These structures are fitted to each 65 other and to a suitable inclosure with insulating material interposed between. Structures of this kind are here under consideration.

In the drawing, letter A indicates ice compartments and letter B indicates provision compartments. These compartments may be contained in independent structures, or one structure may be subdivided to form a plurality of compartments. In the drawing, 70 Fig. 1, shows a structure so subdivided by an integral partition D, the compartment above this partition forming an ice compartment and the one below thereof forming a provision compartment. Fig. 5, on the right, 75 shows a structure subdivided in a similar manner.

Numerals 8 and 9 indicate respectively 85 top and bottom of these structures. 10-10 are the sides thereof and 11 indicates the back of each. The ice is supported above partition D in any suitable manner and cold air is admitted to the compartment below through an opening 12. Water resulting 90 from the melting ice is permitted to drain through an opening 13 and the upper side of partition D may slightly slope toward this opening.

An integral marginal curb 14 is provided 95 at the front edge of partition D to prevent any water from passing over said edge. This curb is also extended along one edge of opening 12, as shown at 15, for the same purpose, and a hood 16 integral with the structure is provided above this opening to 100 prevent any water from dripping through the same.

Circulation of air is rendered possible by permitting warmer air to pass out of the compartment below the ice compartment for 105 which purpose an outlet opening 17 is provided. In the arrangement shown in Fig. 1, this opening is provided in partition D.

As shown in Fig. 5, it is provided in one of the sides 10, the one nearest the additional provision compartment, this latter having a similar opening 18 opposite opening 17.

5 In the arrangement shown in this figure the circulation is completed by additional aligned openings 19 and 21.

Flue collars 22 are interposed in each case between the opposite openings. In the 10 arrangement shown in Fig. 1, the circulation is completed by a flue, the wall 23 of which is also integral with the structure, said flue rising from opening 17 and terminating below top 8. Water draining 15 through opening 13 is received by a tubular waste-duct F formed also integral with the structure and guided thereby toward an outlet 24, provided with a nipple 25 to permit fitting of a waste-pipe. This waste-duct is 20 preferably open in front as shown at f in Figs. 1 and 3, to facilitate cleaning. At its upper end it has a funnel-shaped enlargement to more readily catch the waste water and also any condensation which may form 25 on the under side of partition D and which is caused to drain toward the waste-duct by the slope of this underside. The upper edge of this enlargement is spaced from this underside as shown at d to permit such 30 drainage.

Outlet 24 is air-trapped by means of a body of water held between a neck 26 and a somewhat higher curb 27, the outlet being closed by a cap 28, the lower edge of which 35 dips into the water. The cap rests upon neck 26 from which it is held spaced by means of lugs 29.

31 are ledges positioned opposite each other and provided integrally with the sides 40 of the structure. They serve for the purpose of supporting shelves.

Having described my invention, I claim as new:

1. A lining for refrigerators comprising a 45 main body consisting of continuous vertical side and back walls and horizontal top and bottom walls and having an open front, an intermediate horizontal partition dividing such body into a food and a superposed ice compartment both accessible through said open front, said lining being provided adjacent to one of said vertical walls with a drain opening, said last mentioned vertical wall being provided with a pair of laterally 50 projecting ribs formed integrally with said wall and affording an open sided drain duct leading downwardly from said opening in the partition, said several walls and partition being formed of glazed earthenware integrally united into a unitary structure.

2. A lining for refrigerators comprising a 55 main body consisting of continuous vertical side and back walls and horizontal top and bottom walls and having an open front, an 60 intermediate horizontal partition dividing

such body into a food and a superposed ice compartment both accessible through said open front, said lining being provided adjacent to one of said vertical walls with a drain opening, the top and bottom faces of 70 said partition sloping downwardly toward said opening, said last mentioned vertical wall being provided with a pair of laterally projecting ribs formed integrally with said wall and affording an open sided drain duct 75 leading downwardly from said opening in the partition, said ribs diverging at their upper ends, and said several walls and partition being formed of glazed earthenware integrally united into a unitary structure.

3. A lining for refrigerators comprising a main body consisting of continuous vertical side and back walls and horizontal top and bottom walls and having an open front, an intermediate horizontal partition dividing 85 such body into a food and a superposed ice compartment both accessible through said open front, said horizontal partition and bottom each provided adjacent to one of said vertical walls with a drain opening, said last 90 mentioned vertical wall being provided with a pair of laterally projecting ribs formed integrally with said wall and affording an open sided drain duct between said two openings, said several walls and partition 95 being formed of glazed earthenware integrally united into a unitary structure.

4. A lining for refrigerators comprising a main body consisting of continuous vertical side and back walls and horizontal top and bottom walls and having an open front, an intermediate horizontal partition dividing such body into a food and a superposed ice compartment both accessible through said open front, said partition being provided adjacent to one of said vertical walls with an elongate opening forming a cold air flue and further provided with an integrally formed upwardly extending curb around said opening, and a hood formed integrally 100 with said last mentioned vertical wall above the opening in said partition and extending laterally in all directions beyond the curb surrounding said opening, said several walls, partition and hood being formed of glazed 105 earthenware integrally united into a unitary structure.

5. In a glazed earthenware lining for refrigerators, the combination of an integrally formed body portion consisting of vertical 110 side and back walls, horizontal top and bottom walls, and an intermediate horizontal partition dividing such body into a food and a superposed ice compartment, said partition being provided with an opening forming a cold air flue; a second integrally formed body portion forming a second food compartment and comprising vertical side and back walls and horizontal top and bottom walls, one of the vertical walls of said first 115

named body portion being placed adjacent to but spaced at an interval from one of the vertical walls of said second named body portion, and said adjacent vertical walls being provided with registering openings at the top and bottom portions thereof; and collars connecting said registering openings and forming air circulation flues, the lower collar forming a flue between said food compartments, and the upper collar a flue between the ice and the second named food compartment. 10

In testimony whereof, I hereunto affix my signature in the presence of two witnesses.

CHARLES TETTENBORN.
